UNITED STATES PATENT OFFICE.

SALVATORE A. TENUTA, OF CHICAGO, ILLINOIS.

BUCKLE.

Application filed June 9, 1922. Serial No. 566,942.

To all whom it may concern:

Be it known that I, SALVATORE A. TENUTA, a citizen of the United States, and a resident of the city of Chicago, in the county of Cook and State of Illinois, have invented certain new and useful Improvements in a buckle; and I do hereby declare that the following is a full, clear, and exact description of the same, reference being had to the accompanying drawings, and to the numerals of reference marked therein, which form a part of this specification.

This invention relates to a buckle primarily designed as a suspender buckle.

And it is an object of this invention to provide a simple buckle that is readily adjustable with respect to its support and which directly engages the part it is to hold.

This invention comprises the novel structure hereinafter described and more particularly pointed out and defined in the appended claim.

In the accompanying drawings, which illustrate a preferred embodiment of this invention and in which similar reference numerals refer to similar features in the different views:

Figure 1 is a plan view of the buckle attached to a suspender strap and buckle to a garment.

Figure 2 is a section on the line 2—2 of Figure 1.

Figure 3 is a view similar to Figure 2, illustrating the manner of attaching or removing the buckle from the button of a garment, and Fig. 4 is a plan view of the buckle.

In the exemplification of this invention, there is illustrated a buckle preferably stamped from a thin piece of metal and having transverse openings or slots 1 and 2 separated by a transverse strip 3, the upper edge of the slot 1 being provided with inwardly inclined tangs 4. The lower end of the buckle is provided with a button re-

ceiving opening 5 which is sufficiently wide at its upper end to receive a button or the like in tilted position and which tapers downwardly and merges into a restricted opening or recess 6 adapted for engaging the shank 7 or stitching of the button, a constricted throat 6' being provided for said opening 6 which will serve still better to retain the shank or stitching against accidental displacement.

The foregoing described buckle is adapted to be secured to a suspender strap 8 or the like as shown in Figures 1, 2 and 3 by inserting the strap from the rear through the opening 1 and then through the opening 2 allowing the end to dangle down behind the buckle, the tangs piercing the strap and securing the buckle thereto. A button 9 or the like sewed upon a garment such as a pair of overalls, is adapted to be passed through the opening 5 of the buckle by tilting said button as shown in Figure 3 for suspending the garment from said suspenders as is obvious.

I am aware that numerous details of construction may be varied through a wide range without departing from the principles of this invention, and I therefore do not purpose limiting the patent granted otherwise than necessitated by the prior art.

I claim as my invention:

A suspender buckle, comprising a member having a pair of adjacent transverse slots, the upper wall of one slot having tangs, the lower end of said buckle having an opening enlarged at its upper end for receiving a button in tilted position, said opening merging into a smaller lower opening having a constricted throat.

In testimony whereof I have hereunto subscribed my name in the presence of two subscribing witnesses.

SALVATORE A. TENUTA.
